UNITED STATES PATENT OFFICE.

ALBERT W. ALLEMEIER, OF TOLEDO, OHIO, ASSIGNOR TO THE WOODCRAFT COMPANY, OF TOLEDO, OHIO, A CORPORATION OF OHIO.

ARTICLE OF FURNITURE.

Application filed May 2, 1925. Serial No. 27,388.

To all whom it may concern:

Be it known that I, ALBERT W. ALLEMEIER, a citizen of the United States, and a resident of Toledo, in the county of Lucas 5 and the State of Ohio, have invented a new and useful Article of Furniture.

This invention relates to furniture and is particularly concerned with furniture of the class in which it is desired to increase the supporting area at the will of the 10 user.

Objects of this invention are to provide an article of furniture having an extensible member which may be moved to such a position that the supporting area is increased; 15 to provide a new and improved extensible supporting member for articles of furniture having the unique features of arrangement and operation hereinafter described; and 20 to provide sustaining means for such supporting member having the novel features hereinafter pointed out.

The invention is shown by way of illustration in the accompanying drawings, in 25 which—

Figure 1 is a side elevation partly in section of a couch of the davenport type embodying the invention; Fig. 2 is a top plan view with some of the parts broken away, 30 of the couch shown in Fig. 1; Fig. 3 is a section on the line 3—3 of Fig. 1; Fig. 4 is a perspective of the corner construction of the couch; Fig. 5 is a section on the line 5—5 of Fig. 1; Fig. 6 is a transverse sectional view of the couch showing the extensible supporting member in one position. Fig. 7 is a fragmentary sectional view showing the extensible supporting member in another position of adjustment, and Fig. 8 35 is a view similar to Fig. 7 showing the supporting member in position of use.

The illustrated embodiment of the invention comprises a couch consisting of a frame of wood or other suitable material having front and rear longitudinal frame members 1 and 2, which are connected at their ends by cross members 3 and supporting the front end of the couch are a pair of legs 4. The rear end of the couch is supported by legs 5 which extend upwardly and outwardly to provide upright supports 6 for the back of the couch. Extending longitudinally of the couch and connecting the uprights 6 intermediate the ends thereof is 40 a brace 7, and connecting the upper ends

of the uprights 6 is a brace 8 which is connected to the brace 7 by rods 9. Supported on the front legs 4 and joining the braces 1 and 3 are upwardly and outwardly extending arms 10 which are connected to the rear uprights 6 by the side arms 11. A strip 12 extends across the front of the couch and the opposite ends thereof are connected to the uprights 10 by angle brackets 13 which are secured to the respective parts 65 by screws. As shown a space is provided between the ends of the strips 12 and uprights 10 for a purpose hereinafter described.

Secured to the braces 2, 3 and the strip 12 70 is a substantially flat member 14 providing the seat or supporting surface of the couch and on which the spring seat 15' may be mounted. Formed in the front portion of the main support 14 adjacent the opposite 75 ends thereof are slots 15 which are arranged adjacent the angle brackets 13. As indicated by the dotted lines in the drawings the arms 11 may be padded or cushioned at 16 and cushions 17 may be also 80 provided for the back of the couch in any usual or preferred manner.

In order to increase the supporting area of the couch, and to convert the couch into a bed of substantial proportions, an extensible supplemental support is adapted to be normally disposed in nested or telescoping engagement with the couch structure. The supplemental support comprises a flat surface 18 to the forward edge of which is 85 connected a facing strip 19 which extends the entire length thereof. Connected to the opposite ends of the supporting member are strips 20 which are provided at the inner ends thereof with depending cam pieces 21, 90 the surrounding edges of which are covered by metal strips 22 which are bent to provide stops 23 at the rear end of the supplemental support. Formed in the cam pieces 21 and extending longitudinally of the supplemental support are slots 24. The strip 1 is provided with upwardly and outwardly curved cam surfaces 25 which are arranged to be engaged by the cam pieces 21 when the supporting member is moved outwardly from 95 the couch structure.

It will be apparent that by sliding the supplemental support outwardly a sufficient distance the cam pieces 21 adjacent the rear end thereof engage the cam surfaces 25 of 100 110

the strip 1. Further outward movement causes the supplemental support to move upwardly approaching the horizontal plane of the main support 14 of the couch (Fig. 7). Thereupon the stops 23 abut against the angle brackets 13 to arrest further outward movement of the supplemental support. In this position of the supplemental support a slight space is left between the rear end thereof and the forward end of the main support 14.

In order to hold the supplemental support in approximately the horizontal plane of the main support 14, a pair of rods 26 are connected to the rear face of the strip 12 by sleeve brackets 27 to have sliding movement therein. For conjointly moving the rods 26 outwardly to bridge the space between the end of the strip 12 and the uprights 10, a lever 28 is fixed intermediate its ends to a pin 29, and the ends of the rods 26 are pivoted to opposite ends of this lever. An actuating handle 30 is fixed to the opposite end of the pin and by rotating this handle in one direction both rods 26 are forced outwardly into the slots 24 of the cam member 21. Thereafter the supplemental support may be moved rearwardly toward the main support 14 to lie in approximately the same horizontal plane. The supplemental support is further aligned and positioned relatively to the main support 14 by pins 31 fixed to the rear face of the strip 19, these pins being arranged to project into suitable apertures formed in the strip 12.

In order to support the outer end of the supplemental support, legs 32 are pivoted at one end thereof adjacent the facing strip 19 between parallel bars 33, so that when the supplemental support is moved outwardly for use the legs 32 may be swung downwardly and outwardly at substantially right angles, as indicated in Fig. 8.

For returning the supplemental support to telescoping position, the support is first moved outwardly to permit access to the actuating member 30 which is thereafter rotated to withdraw the rods 26 from the slots 24. The legs 32 are then swung upwardly to the position indicated in Fig. 6, and thereafter the supplemental support is moved inwardly upon supporting guideways 34 which extend transversely of the couch and are connected at opposite ends to the frame members 1 and 2 respectively. In this position the finishing strip 19 abuts against the cross-piece 12, and the outer ends of this strip are approximately co-incident with the outer surface of the uprights 10, thereby presenting a finished appearance to the structure and effectively concealing the supporting member.

An outstanding characteristic of the invention resides in the provision of an ex-

tensible supporting element which normally may be disposed concealed in telescoping relation to the remainder of the structure and which, when desired, may readily be moved to useful position in approximate alignment 70 with the main support. A further feature of the invention consists in the provision of the unique mechanism heretofore described which is readily accessible from the outside of the structure for locking the extensible 75 support in proper position relative to the main support for use in conjunction therewith.

The spring seat 15' heretofore mentioned may include the usual padded cushions and 80 wire springs commonly employed in couches of the davenport type. The cardinal advantage of positioning the extensible supplemental support in the manner indicated is that it in no way interferes with the cushioning action of the springs and other cushioning structure because it is located below the main support 14 upon which the cushioning structure is supported. This is a marked improvement over prior couch constructions in which extensible supports have 90 portions projecting into the spring arrangement because these projecting portions interfere materially with the efficient action of the springs. 95

While this invention has been shown and described in connection with a couch, it is to be understood that an extensible supporting member of the character described may be used to advantage in desks, chairs and other 100 similar articles of furniture, and while I have shown and described a construction which is the best known to me at the present time, numerous modifications and changes in details of arrangement, construction and 105 in the application may be effected without departing from the invention, especially as defined in the appended claims.

Having thus described my invention, what I claim as new and desire to secure by Letters Patent is:

1. An article of furniture having a base portion provided with a guideway, a supporting surface above said guideway, a supplemental support slidable on said guideway, said guideway having slots, cam elements on said support depending into said slots whereby when said support is moved outwardly on said guideway the cam elements engage one end of the slots and elevate said support to approximately the horizontal plane of said surface in spaced relation thereto, and means for engaging said support for holding one side thereof in position, the connection between said holding means and support permitting relative movement therebetween whereby said support may be moved into close juxtaposition to said supporting surface. 120

2. An article of manufacture having a 130

base portion, a supporting surface, a supplemental support normally disposed beneath said surface, said support being horizontally extensible to one side of said surface, 5 means for elevating said support to a plane approximately coincident with the plane of said surface, one of said parts having an elongate slot, a movable rod on another part, and means for actuating said rod whereby 10 when said support is fully extended said rod may be moved into said slot thereby to enable the support to be held in elevated position and to be moved independently of the rod into close juxtaposition with said surface. 15

3. A davenport having a main frame provided with a seat, an extensible frame carried by the main frame, means on opposed portions of said extensible frame for elevating same to approximately the plane of said seat and in forwardly spaced relation to the front thereof when the same is moved outwardly from the main frame, means movable with relation to the extensible frame and 25 into and out of engagement with said elevating means for holding said extensible frame in elevated position and for permitting the same to be moved rearwardly into close juxtaposition with said seat front and manually controlled means for moving the holding means into and out of engagement with the elevating means. 30

4. A davenport having a main frame provided with a seat, an extensible frame carried by the main frame, means for elevating said extensible frame to approximately the plane of the seat in forwardly spaced relation to the front thereof, and other means engageable with and movable relative to and

into and out of engagement with said extensible frame for holding the same in elevated position and for permitting the same to be moved rearwardly into close juxtaposition with said seat front. 40

5. A davenport including a main frame 45 having a seat, an extensible frame, means for elevating the extensible frame into substantially the plane of the seat and for disposing same spaced forwardly of the main frame, and means carried by the main frame 50 and movable into and out of engagement with the extensible frame for holding the latter in substantially the plane of the seat and for permitting the extensible frame to be moved rearwardly to substantially close 55 said space between the main frame and the extensible frame and while said holding means remains stationary.

6. A davenport including a stationary frame having a seat, an extensible frame below the seat, means for elevating the extensible frame into substantially the plane of the seat, and for disposing the extensible frame spaced forwardly of the stationary frame, and permitting movement of the extensible frame rearwardly to contact with the stationary frame, and manually operable means movable into and out of latching position, relative to the extensible frame for latching same in elevated position and for 60 permitting said rearward movement thereof to substantially close the space between the stationary frame and the extensible frame, said latching means upon release permitting 65 the extensible frame to be lowered. 70

In testimony whereof I have hereunto signed my name to this specification.

ALBERT W. ALLEMEIER.
